CLAIM

The ornamental design for a shower bag as shown and described.

DESCRIPTION

FIG. 1 is a left, front and top perspective view of a shower bag showing my new design;

FIG. 2 is a front elevational view thereof;

FIG. 3 is a rear elevational view thereof;

FIG. 4 is a right view thereof;

FIG. 5 is a left view thereof;

FIG. 6 is a top plan view thereof;

FIG. 7 is a bottom plan view thereof; and,

FIG. 8 is a right, rear and bottom perspective view thereof.

The evenly broken lines illustrate portions of the shower bag that form no part of the claimed design.

1 Claim, 8 Drawing Sheets
